UNITED STATES PATENT OFFICE

MONTAGUE HENRY BARLING, OF CAMDEN TOWN, LONDON, ENGLAND

ABSORBENT LINER OR INNER TUBE FOR TOBACCO PIPES, CIGAR AND CIGARETTE TUBES

Application filed October 17, 1927, Serial No. 226,657, and in Great Britain February 16, 1927.

This invention relates to removable inner tubes or liners for tobacco pipes, cigar and cigarette tubes for absorbing the moist products resulting from the combustion of the 5 tobacco and which are arranged in the bore of the said pipes or the like, and are commonly made of absorbent paper rolled in tubular form, the edge of the exterior portion or layer of each liner being usually cemented in position.

In practice, the moist products absorbed by these liners in course of time permeate the substance, and exude from the exterior surface thereof, so that they become friable and break when being removed and also cause the bore of the pipe or the like to become fouled, and to avoid this disadvantage it has been proposed to provide the tube with a non-permeable sheath or covering.

According to my invention I provide absorbent inner tubes of the described kind, and preferably sterilized, with a non-permeable sheath or covering, made of metal foil, rolled or wrapped around each inner tube and cemented in position. A layer of gauze fabric may also be arranged between the absorbent material and the non-permeable covering or sheath, which in this case may be in the form of a metal tube.

In practice, the improved inner tube is advantageously made of such a length that it lies partly in the bore of the tobacco pipe or like stem and partly in the bore of the mouth-piece thereof, these portions of the two bores being enlarged to form a chamber shouldered at each end to butt against the two ends of the absorbent inner tube.

To enable the invention to be fully understood I will describe it by reference to the accompanying drawing, in which:—

Figure 1 is a longitudinal section of a tobacco pipe provided with a liner or inner tube, in accordance with the invention.

Figure 2 is a sectional side view of a portion of the liner or inner tube, detached from the pipe and drawn to a larger scale than Figure 1.

Figure 3 is a cross-section of the said liner or inner tube.

Figures 4 and 5 are views similar to Figures

2 and 3 respectively, illustrating slight modifications of the liner or inner tube.

a is the tobacco pipe having the bowl *b* and stem *c* provided with the axial passage or bore *d* communicating with the bowl, and *e* is the mouth-piece having the axial passage or bore *f* aligning with the passage *d* and also having the spigot *g* fitting within the socket *h* in the said stem *c* in the usual manner.

i is the liner or inner tube and *j* is the chamber in the stem and mouth-piece to receive the said liner and which chamber is formed by enlarging the passages *d* and *f*, the ends of the said chamber forming shoulders which butt against the ends of the liner, as indicated clearly in Figure 1. *k* is the roll of absorbent paper preferably sterilized forming the liner *i* and *l* the layer of foil applied to the exterior of the said roll *k* to prevent its breaking when being removed and to prevent the absorbed moisture from contaminating the bore of the pipe or the like.

m, Figures 4 and 5, is the layer of gauze which I find it advantageous to apply between the absorbent body of the liner and the non-permeable exterior thereof, which latter, in this case, is shown in the form of a tube of metal.

Claims:

1. As a new article of manufacture, an absorbent liner for tobacco pipes, cigar and cigarette tubes, comprising a unitary structure consisting of a tubular body of absorbent friable material providing an unobstructed smoke passage therethrough, and an exterior covering of material non-permeable by moisture surrounding the absorbent tube to protect from moisture the walls of the smoke passage in which it is inserted, and to facilitate the removal of the liner intact, therefrom.

2. As a new article of manufacture, an absorbent liner for tobacco pipes, cigar and cigarette tubes, comprising a piece of absorbent paper rolled into cylindrical form and providing an unobstructed smoke passage therethrough, and an exterior covering of metallic foil surrounding and permanently secured to the absorbent tube to protect from moisture the walls of the smoke passage in

which it is inserted, and to facilitate the removal of the liner intact, therefrom.

3. As a new article of manufacture, an absorbent liner for tobacco pipes, cigar and cigarette tubes, comprising a cylindrical roll of absorbent paper providing an unobstructed smoke passage therethrough, a layer of gauze fabric surrounding said absorbent roll and united thereto to prevent breakage of the absorbent paper when saturated with moisture, in removing it, and an exterior covering of metallic foil surrounding said gauze fabric and united thereto to protect from moisture the walls of the smoke passage in which the liner is used and to facilitate the removal of the liner intact, therefrom.
